UNITED STATES PATENT OFFICE.

EMIL KERNEN, OF WEINER, ARKANSAS.

MANURE-LOADER.

1,339,263.

Specification of Letters Patent.

Patented May 4, 1920.

Application filed April 5, 1919. Serial No. 287,757.

To all whom it may concern:

Be it known that I, EMIL KERNEN, a citizen of Switzerland, residing at Weiner, in the county of Poinsett and State of Arkansas, have invented new and useful Improvements in Manure-Loaders, of which the following is a specification.

This invention relates to means for loading material such as manure and the like, from a pile or stack to a vehicle and the principal object of the invention is to provide a derrick mounted on a wheeled truck with means thereon for operating the lifting forks to transport the material from the pile to a wagon.

The invention relates to the means for raising and lowering the fork and for emptying the same and also to the means for rotating the derrick to carry the fork from the pile to the wagon and back to the pile.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side elevation of the invention;

Fig. 2 is an end view thereof with parts in section;

Fig. 3 is a plan view with parts omitted;

Fig. 4 is an enlarged view of the fork;

Fig. 5 is a side view of the fork.

In these views 1 indicates a wheeled truck to the center of which is secured a cylindrical upright member 2. An annular track 3 formed of rollers or the like is formed on the upper face of the truck around said upright. 4 indicates a rotatable platform having its outer edges supported on said track and having a centrally located opening through which the member 2 passes. An inner track 5 is provided adjacent said cylindrical member on which the inner edge of the platform rests. This platform carries a tubular upright member 6 which surrounds the cylindrical member, as shown. This member 6 has pivoted thereto the inner end 55 of the boom 7. The outer end of said boom is adjustably connected to the upper end of

the cylindrical member by the cable 8. The platform 4 supports the motor 9, which may be of any desired form. The drive shaft of this motor is connected with the horizontal shaft 10 suitably journaled on the platform, by the chain 11 and the chain wheels 12. This shaft 10 is located to one side of the tubular member, as shown. A pair of parallel shafts 13 are suitably journaled on the platform and one of said shafts is connected with the shaft 10 by the chain 14 and the wheels 15. The two shafts 13 are geared together by means of the wheels 16. The outer ends of the shafts 13 are connected to the movable shafts 17 by the universal joints 18. The outer ends of the movable shafts 17 carry the gear wheels 19 and said outer ends are journaled in the tiltable member 20 which is connected with the hand lever 21. In this way when the hand lever is moved from one side to the other one of said shafts will be swung downwardly while the other shaft will be swung upwardly to throw the gear wheels 19 into and out of engagement with a circular track 22 secured to the truck. It will thus be seen that when one of the gears 19 is in engagement with the track and the motor is started the platform will be rotated in one direction and when the other gear wheel is in engagement with the track the platform will be rotated in the opposite direction. When both of the gears 19 are out of engagement with the track the platform will remain stationary. The tubular member 6 supports a pair of reels 23, one on one side thereof and one on the other, these reels being supported by the stub shafts 24 which have their inner ends suitably secured to the tubular member. The reels are provided with pawl and ratchet means for holding them stationary when they are not connected with the engine. One of the reels is provided with an extension shaft 24' which is adapted to be engaged and disengaged with the reel by the clutch member 25, actuated by the hand lever 26. This extension shaft 24' carries a sprocket wheel 27 which is connected with a wheel 28 on the engine shaft by a chain 29. The shaft 24' also carries a chain wheel 30 which is connected with a wheel 31, connected with the upper reel by means of the chain 32. The upper reel 23 may be moved into and out of engagement with the wheel 31 by means of the lever 33. A cable 34 passes from one of the reels over a pulley 35 on the end of the

boom and downwardly to the fork 36 so that by rotating the said reel, the said cable will raise the fork. When the fork is to be lowered the pawls are disengaged from the 5 ratchets so as to permit the form to drop by gravity with the wheels running free. Said cable is secured to the pivotal point of the fork members by the clip 37. A second cable 38 passes from the other reel around 10 a second pulley 39 on the end of the boom and the end of this cable is fastened to a cable 40 which has its ends connected with the upper ends of the fork members. Thus when the reel connected with said cable 38 is 15 actuated to wind up said cable said cable acting on the cable 40 will draw the upper ends of the fork members together to cause the prongs of the fork to grip the material.

This fork member is composed of two jaw 20 members 41 and 42 pivoted intermediate their ends with the upwardly extending arms connected with the cable 40 as before described. These arms are normally pulled apart by the springs 43. The lower part of 25 the jaw members are provided with laterally extending arms 44 to which the prongs 45 are connected. As shown in the drawings, there are four prongs to each jaw member.

30 The truck is pulled to the pile of material to be loaded and then the engine is started to rotate the platform to place the fork above said pile. The platform is then held stationary while one of the reels is dis- 35 connected from its pawls to permit the cable 34 to run out so that the fork will drop into the pile. The fork is sufficiently heavy to cause its prongs to enter the pile. As the fork drops the springs 43 will cause the jaws 40 to open. While this is taking place it will, of course, be understood that the other cable is slack to permit the jaws to open. The other reel is then connected with the engine to wind up the cable 38 to cause the cable 40 45 to close the jaws and then both reels are ac-

tuated to wind both cables to lift the fork from the pile. The platform is then rotated to swing the boom over the wagon and then the reels are released from the pawls to permit the fork to drop by gravity and 50 when in proper position the cable 38 is slackened to permit the jaws to open to release the load.

It is thought from the foregoing description that the advantages and novel features 55 of my invention will be readily apparent.

I desire it to be understood that I may make changes in the construction and in the combination and arrangement of the several parts, provided that such changes fall 60 within the scope of the appended claims.

What I claim is:—

1. An apparatus of the class described comprising a truck, a platform rotatably mounted on the truck, a circular rack on the 65 truck adjacent said platform, a pair of movable shafts carried by the platform, gears on said shafts engaging the rack, power means for driving said shafts and means for moving the shafts to place one or the other 70 of the gear wheels in engagement with the rack.

2. An apparatus of the class described comprising a truck having an upright member thereon, a platform rotatably mounted 75 on the truck and having a central opening through which the upright member passes, a tubular upright member on said platform surrounding the first mentioned upright member, a boom carried by said tubular 80 member, reels carried by said tubular member, an engine on the platform, means for connecting the same with the reels, a receptacle, cables connecting the same with the reels, pulleys on the boom over which the 85 cable passes and means actuated by the engine for rotating the platform.

In testimony whereof I affix my signature.

EMIL KERNEN.
